US00D956925S

(12) **United States Design Patent** (10) **Patent No.:** **US D956,925 S**
(45) **Date of Patent:** **** Jul. 5, 2022**

(54) **FLUID CARTRIDGE**

(71) Applicant: **Graco Minnesota Inc.**, Minneapolis, MN (US)

(72) Inventor: **Daniel P. Ross**, Vadnais Heights, MN (US)

(73) Assignee: **Graco Minnesota Inc.**, Minneapolis, MN (US)

(**) Term: **15 Years**

(21) Appl. No.: **29/808,038**

(22) Filed: **Sep. 16, 2021**

Related U.S. Application Data

(63) Continuation of application No. 29/710,788, filed on Oct. 25, 2019, now Pat. No. Des. 933,160, which is a continuation-in-part of application No. 29/698,843, filed on Jul. 19, 2019, now Pat. No. Des. 904,563.

CLAIM

The ornamental design for a fluid cartridge, as shown and described.

DESCRIPTION

FIG. 1 is a perspective view of a consumable fluid cartridge; FIG. 2 is a rear elevational view of the consumable fluid cartridge;

FIG. 3 is a front elevational view of the consumable fluid cartridge;

FIG. 4 is a left side view of the consumable fluid cartridge; FIG. 5 is a right side view of the consumable fluid cartridge; FIG. 6 is a top plan view of the consumable fluid cartridge; and,

FIG. 7 is a bottom plan view of the consumable fluid cartridge.

The broken lines shown represent portions of a fluid cartridge and form no part of the claimed design.

1 Claim, 3 Drawing Sheets
